UNITED STATES PATENT OFFICE.

RUDOLF SCHWIEDER, OF DRESDEN, GERMANY.

WRINGER-ROLL.

931,804.

Specification of Letters Patent. Patented Aug. 24, 1909.

Application filed December 21, 1908. Serial No. 468,616.

To all whom it may concern:

Be it known that I, RUDOLF SCHWIEDER, a subject of the Emperor of Germany, residing at 150 Grossenhainerstrasse, Dresden, N., in 5 the German Empire, have invented certain new and useful Improvements in Wringer Rolls, of which the following is a specification.

My invention relates to improvements in 10 wringer rolls and consists in constructing said rolls with hollow cores drawn of one piece of metal and reduced at both ends to form journals, longitudinal grooves being provided to hold a rubber coating on the 15 core.

In the annexed drawings the invention is 20 illustrated, Figure 1 representing a cross section of the two rolls of a wringing machine, Fig. 2, a front view of a core without coating, and Fig. 3, an end portion of a roll in longitudinal section.

The roll consists of a drawn, hollow steel core *f*, the ends *g* of which are reduced to 25 form the journals *h*, said journals being closed by plugs *i* which may be either screwed in or welded to the journals in any

suitable manner. The outer surface of the core is provided with grooves *k* for the purpose of effecting a rigid joint between said core and its rubber coating, *l*.

Wringer machines constructed with rolls of this description will be considerably lighter than those commonly used, and also more efficient owing to the elasticity of the core. The rubber coating may be made of a 35 thickness simply sufficient to protect the washing.

The closing of the ends or journals of the rolls serves to prevent the water from entering into the interior of the same and so to 40 corrode the steel core.

I claim:—

A roll for wringing machines comprising a hollow, drawn steel core having grooves to 45 hold a rubber coating, journals on said core formed by reducing the ends of the same, and plugs inserted in said journals to close the latter, substantially as set forth.

RUDOLF SCHWIEDER.
